UNITED STATES PATENT OFFICE.

GEORGE C. F. WILLIAMS, OF HARTFORD, CONNECTICUT.

NAIL-STRING MACHINE.

1,397,191.

Specification of Letters Patent. Patented Nov. 15, 1921.

Application filed August 10, 1916, Serial No. 114,411. Renewed July 18, 1921. Serial No. 485,792.

To all whom it may concern:

Be it known that I, George C. F. Williams, a citizen of the United States, residing in Hartford, Connecticut, have invented 5 the following described Improvements in Nail-String Machines.

The invention is an improvement in continuous nail rolling machines for producing what is known in the art as a nail-string or 10 a string or strip of connected, partially formed nail blanks, for use in the manufacture of horseshoe-nails, and the improvements consist in the organization and operation of the successive rolling dies of such a 15 machine whereby the stock, in continuous form, is caused to pass in a helical path through all of said dies to produce a completed nail string in a single machine, thereby resulting in economy of floor space and in 20 other advantages which will be apparent from the description which follows.

In the accompanying drawings, Figure 1 illustrates in perspective, although more or less diagrammatically, the essential features of my invention and the relation of the 25 principal parts of a machine incorporating said invention, and also the path of the stock therethrough as above described, without however, showing in detail all the stock 30 guiding means.

Fig. 2 illustrates in section and partly in elevation the principal parts of said guiding means; and

Fig. 3 a plan view also with parts omitted. 35 Fig. 4 is a cross section of a friction holder.

Referring to these figures, the machine consists of a single bed plate having a main drive shaft 1 journaled on it and carrying 40 the housings 2 upstanding thereon for some six or more pairs of die rolls 3. These housings may be assumed to be of appropriate design and provided with adequate bearings for, and proper means of adjustment of, the 45 die rolls which are journaled therein. For convenience of illustration, the drawing indicates these well understood details only in a general way. The several die rolls are mounted in longitudinal positions on the 50 bed and substantially in axial alinement with each other, although exact alinement is not necessary, and each roll carries suitably seated upon and secured to it, an annular set of die blocks marked 4, those on the upper 55 rolls being properly spaced with relation to those on the lower rolls so that their

respective die cavities or surfaces will register as will be understood. All of the die cavities for each pair of rolls are of the same size and represent one of the stages of 60 the development of the rod stock to nail-string form. In the case of the machine illustrated, it is intended that the nail-string shall be reduced from plain stock to final form by six die-rolling operations and hence 65 there are six pairs of coöperating die sets but obviously there is no limitation in this respect and a greater number of sets might be preferred in order to distribute the wear on the machine over a greater number of 70 surfaces.

The several die-carrying rolls or members are driven in the same direction by their respective gears and pinions 5 from their common drive shaft 1, the first pair, (at the 75 left hand of Fig. 1) being driven at a slower rate than the others as presently described.

The continuous metal stock of which the nail string is formed, being a rod of rectangular cross-section, is introduced into the 80 pass between the annular series of die blocks of the first pair of rolls at the end of the machine and on emerging from the dies of these first rolls turns upwardly and obliquely rearward and over to the opposite or 85 entrance side of the pass between the next or second pair of rolls, and so on, through the third pair and the rest of the series, thus describing a substantially helical path through the machine and emerging from 90 the last pass as a finished nail-string. The first pair of die rolls performs the initial rolling operation upon the stock by the pairs of registering die cavities thereon and thereby, for a single revolution, blanks out upon 95 the rod stock as many blanks of the initial stage, as there are die cavities in the set on that pair of rolls; this may be six or more, depending upon the diameter of the roll. The section of stock representing the first 100 spire of the helix is thus constituted by a succession or string of rudimentary blanks all alike and each in its initial stage. The die sets of the second pair of rolls receive and roll this stock in a quarter-turned position from that in which it passed through the first set, in order to roll the edges of the stock as it passes through the first set and the loop or spire of stock between the first and second rolls is large enough to accommodate the helical curvature as well as this quarter-turn without permanent distortion. 110

It is necessary that the blank be rolled alternately on its sides and edges in each succeeding pass throughout the machine and hence each spire is similarly turned a quarter-turn. The second die set rolls the blanks of the first spire to give them the slightly elongated form of the second stage of development and receives the stock from the first spire under the guidance of a curved feed tube or channel 9 and also under the retarding influence of a friction holder mechanism whereby the entering blanks are held back and thereby caused to register with the several die cavities of the said second set of die blocks. Similar guide tubes and friction holders are supplied to the entrance of the pass of each succeeding pair of die rolls, but as all operate in exactly the same way, only one, that for the last pass, is illustrated in the drawing. The friction holder consists of a base mounted on a frame bracket 11 and provided with a stock groove 12 leading directly into the pass of the rolls. A friction shoe 13 is appropriately mounted on the base and provided with a tongue entering the groove, and pressed against the stock therein by the action of a spring 14, the latter being controlled by a cam lever 15. The construction is clearly shown in Fig. 4. In every alternate friction holder the groove receives the stock on edge thus constituting the means whereby the quarter-turn is imparted to the successive spires. The die-cavities around all of the rolls except the first are separated by clearance spaces having no advancing effect on the stock as illustrated in Fig. 2, and the friction holders coöperate with these spaces to retain the stock in position where the nail head cavities of each block will register with the head formation on the stock as they come into engagement with it. The die cavities of the first pair of rolls are continuous around each roll as shown in Fig. 1, that is to say, with no clearances between them, and the rate of rotation of these rolls, and of the advance of the stock therethrough, is constant and suited to maintain a constant length of stock in the first spire. This means in practice that the first rolls deliver into the first spire as many blanks as the second pair of rolls takes in, in one rotation. All of the succeeding pairs of rolls deliver an equal number of blanks on each rotation and all said rolls are driven at the same speed.

On the delivery side of each pair of die rolls, the issuing stock is received in a channel 16 formed in a bracket 17, and which is curved upwardly to give the stock an easy upward direction preparing it to follow its helical path. Each upstanding spire of stock is supported and steadied by a horizontal rod, 18, carried on posts rising from the machine frame, or which may, if desired,

be otherwise supported as, for instance, from the ceiling of the room in which the machine is installed.

The operation of the machine will be apparent from the description above given and it will be evident that by mounting the whole series of die sets upon a common frame and driving them from a common drive shaft journaled in the same frame and also by leading the stock through the helical path, the machine provides a nail-rolling equipment extremely reliable and positive in action and of most compact form as compared to prior equipment for making the same product. It is to be understood, moreover, that except as specified in the claims, the invention is not limited in respect to the size, proportion or relative arrangement of the various parts above described, and that various substitutions, modifications, subtractions from and additions to the apparatus illustrated may be resorted to without departing from the invention.

I claim—

1. A nail-string machine comprising a series of successively arranged pairs of rotary die sets having die-cavities suited for successively die-rolling a continuous rod stock to nail-string form, a drive-shaft for driving all the die sets and guiding means for directing the stock in a substantially helical path through the successive passes between said pairs of die sets.

2. A nail-string machine comprising a frame, a series of successively arranged pairs of rotary die sets journaled thereon and suited for successively die-rolling a continuous rod stock to nail-string form, a drive-shaft common to all said die sets and driving the same in the same direction and means for guiding said stock in a substantially helical path through said series of die sets and imparting a quarter-turn to the stock between the passes thereof.

3. A nail-string machine comprising a frame, a series of successively arranged pairs of die rolling members journaled thereon, and suited for successively die-rolling a continuous rod stock to nail-string form, a drive-shaft common to all said members, journaled in the frame and driving said members in the same direction, means for guiding the stock in a helical path through said series of members, said means comprising a friction holder on the entrance side of each pass through said members, and co-operating therewith to register the stock with the die-cavities of said members.

4. A nail-string machine comprising a main frame, a series of successively arranged pairs of rotary die sets journaled thereon and suited for successively die-rolling a continuous rod stock to nail-string form, said sets each comprising a plurality of die blocks of the same size of die cavity, in combina-

tion with a drive shaft common to all said members and rotating them in the same direction and means for guiding and directing the said stock in a substantially helical path through said series of die sets.

5. A nail-string machine comprising a series of successively arranged die rolls each carrying a rotary die set and suited for successively die-rolling a continuous rod stock 10 to nail-string form, a drive shaft having separate operating connection to each pair of die rolls and itself journaled in the main frame of the machine and means for directing the stock in a helical path through said 15 series of die sets.

6. A nail-string machine comprising a series of successively arranged pairs of rotary die sets having die-cavities suited for successively die-rolling a continuous rod stock to nail-string form, a drive-shaft for driving all the die sets, guiding means for directing the stock in a substantially helical path through the successive passes between said pairs of die sets, and means for supporting the spires of the helix above the machine.

20 In testimony whereof I have signed this specification.

GEORGE C. F. WILLIAMS.
